3 SHEETS-SHEET 3

UNITED STATES PATENT OFFICE.

BERT W. KING, OF DETROIT, MICHIGAN, ASSIGNOR, BY MÉSNE ASSIGNMENTS, TO THE COMPUTING SCALE COMPANY, OF DAYTON, OHIO, A CORPORATION OF OHIO.

PLATFORM SCALE.

Application filed April 30, 1919. Serial No. 293,738.

To all whom it may concern:

Be it known that I, BERT W. KING, being a citizen of the United States, residing at Detroit, in the county of Wayne and State of Michigan, have invented certain new and useful Improvements in Platform Scales, of which the following is a full, clear, and exact description.

This invention relates to weighing scales, and while certain features are applicable to scales of other types the invention in its present form pertains more particularly to so-called platform counter scales provided with means to indicate the weight or value of the commodities, or both. The chief object of the invention is to provide a simple scale of durable construction which will stand long use without getting out of order. To this and other ends the invention consists in the novel features and combinations hereinafter described.

One form of the invention is illustrated in the accompanying drawings, in which

Fig. 1 is a plan view of the base-lever system, the pedestal being in horizontal section and the base housing or cover being broken away, and the platform removed.

Fig. 2 is a front view and Fig 3 is a side view, portions of the base housing, pedestal and drum casing being broken away to show the interior parts.

The main lever 10 is substantially in the form of a rectangular frame, provided at front i. e., away from the pedestal with two widely spaced forwardly extending lugs 11 having knife-edges 13 resting on the agates 14 suitably mounted on the stationary posts 15 rising from the base 16 and forming the fulcrum. At the rear the lever is provided with two rearwardly extending arms 17, 18, the first connected to a coil spring 19 which counterbalances the platform lever system. The other arm, 18, is connected to an upwardly extending draft-rod 20, more fully described hereinafter.

The auxiliary or secondary lever 21 is a transverse frame arranged inside of the main lever, and is provided with forwardly and rearwardly extending arms 22, 23 at its sides. The latter carry inverted knife-edge pivots 24 engaging agates in the upper ends of the links 25 pivoted at their lower ends on the base 16. These links constitute a swinging fulcrum for lever 21. The arms

22 also have inverted knife-edge pivots 26, 55 on which rests the bearing frame 27. Between the front and rear arms the lever is provided with agates 28 bearing on inverted knife-edge pivots 29 carried by the sides of the main lever 10.

The bearing frame 27, which is roughly triangular in form, carries the platform 30, and at its rear end or apex is provided with a vertical check arm 31 connected at its upper end to a check line 32. As will be seen in Figs. 1 and 2, the check arm 31 is in the form of a channel and extends upwardly in the pedestal 33.

From the foregoing it will be seen (Fig. 3) that the weight of the goods on the platform 30 rocks lever 21 counterclockwise on its swinging fulcrum 25, and that the lever 21 in turn rocks lever 10 clockwise on its fixed fulcrum 15. Considering the weight of the goods to be the "power", it will be seen that lever 21 is of the second class and that lever 10 is of the third class. Lever 10 is preferably bent at the knife-edges 29 so that the latter may range properly with the knife-edges 13 and 34.

The draft rod 20, previously referred to as connected to the main base-lever 10, is forked at its upper end provided with eyes engaging knife-edges 35 (Fig. 2) on a lever 36 in the lower part of the drum housing 37. 85 This lever (of the third class) is fulcrumed at one end in the shackle 38 and at its other end is connected (by the means presently to be described) to the load-counterbalancing springs 51. Fixed by one arm to a pair of depending lugs 40 is a U-shaped thermostat 41 (made up of two metal bars having different coefficients of expansion) which has its other arm connected to a shiftable bar 42 extending parallel to the lever below the same. At one end this bar is connected to a coil spring 43. The other end of the spring is adjustably connected to a lug 44 on the lever by means of a bolt 45 and nut 46. The other end of the rod 42 carries a block 100 47 having side-plates embracing the end of the lever. The block also carries knife-edges 48 engaged by hooks 49 (see also Fig. 3) on the yoke 50 to which the load-counterbalancing springs 51 are adjustably connected by means of nuts 52 and bolts 53 extending from the ears 54. At the top the springs are connected to an equalizer bar 55

pivoted at its center to a support 56 suitably fastened on the adjacent circular end-plate 56a of the drum housing 33.

The dashpot 57 is carried by the yoke 50 and extends downwardly between the arms of the same. The dashpot plunger 58 is pivotally connected at its top to the spring-equalizer support 56.

The drum 59, which may be of the usual computing type, is fixed on a shaft 60 mounted to rotate in ball-bearings in the drum-housing end plates. One end of the shaft has a pinion 61 meshing with a vertical rack 62 pivoted at its lower end to a vertical arm 63 which is itself pivoted on the adjacent end of the lever 36. The rack is also provided with a light counterbalancing weight 64, which urges the rack counterclockwise (as viewed in Fig. 3) and so keeps it in proper mesh with the pinion 61, as will be readily understood.

The operation of the scale described is as follows: When the goods to be weighed are placed on the platform 30, Fig. 3, the lever 21 is rocked counterclockwise drawing down the draft-rod 20 and rocking lever 36 clockwise on its fulcrum 38 against the tension of springs 51. This also moves the rack 62 downwardly and rotates pinion 61 and drum 59.

As the temperature increases, the arm of the thermostat 41 which is connected to the bar 42 (Fig. 2) swings toward the right (because of the different coefficients of expansion of the two metals composing the thermostat) thereby shifting the block 47 outwardly. This lengthens the lever-arm to which springs 51 are connected, thus compensating for the softening of the springs 40 due to the increase of temperature. As the temperature decreases the block 47 is moved inwardly, thus compensating for the stiffening of the springs.

It is to be understood that the invention is not limited to the construction herein specifically illustrated and described but can be embodied in other forms without departure from its spirit as defined by the appended claims.

50 I claim:

1. In a scale, a lever system comprising in combination, a main lever composed of an open frame having a pair of rearwardly extending arms, a spring load counterbalance means connected to one of said arms, a spring lever counterbalancing means connected to the other, a secondary lever pivotally connected to the main lever, a fulcrum for the main lever, a fulcrum for the secondary lever, and a platform support pivotally connected to the secondary lever.

2. In a scale, the combination of a main lever composed of an open frame, load-counterbalancing means connected to the main lever at the rear thereof, a fulcrum for

the main lever, a secondary lever extending from side to side of the main lever and arranged within the same and having fulcrum pivots, bearings for the fulcrum pivots, pivotal means connecting the secondary lever 70 and the main lever to rock the latter, and a platform-support pivotally connected to the secondary lever.

3. In a scale, the combination of a main lever composed of an open frame having a 75 pair of forwardly extending arms provided with pivots and a pair of rearwardly extending arms provided with pivots, fulcrum-bearings for the forward pivots, lever-counterbalancing means connected to one of the 80 rearwardly extending arms and load-counterbalancing means connected to the other, a secondary lever extending from side to side of the main lever within the same and having a pair of rearwardly extending arms 85 provided with pivots and a pair of forwardly extending arms provided with pivots, fulcrum-bearings for the rearward pivots of the second lever, pivotal means connecting the main lever to the secondary lever 90 between the forward and rearward pivots of the latter, and a platform support connected to the forward pivots of the secondary lever.

4. In a scale, the combination of a main 95 lever having a pair of pivots at its rear end, a fulcrum for the lever, a platform support, means operatively connecting the platform support and the main lever to rock the latter on its fulcrum, a spring connected with one of said pair of pivots on the main lever to counterbalance the main lever and the scale parts supported thereby, means connected with the other pivot of said pair to variably counterbalance a 100 load placed on the platform, and indicating means connected to the main lever and responsive to the movements thereof.

5. In a scale, the combination of a main lever composed of an open frame of substantially rectangular form having a pair 110 of forwardly extending arms and a pair of rearwardly extending arms provided with pivots, bearings for the forward pivots, constituting a fulcrum for the main lever, a 115 secondary lever arranged transversely of the main lever within the latter and having a pair of forwardly extending arms and a pair of rearwardly extending arms adjacent to the sides of the main lever, each of said arms being provided with a pivot, swinging bearings for the rearward pivots of the secondary lever, a platform support resting on the forward pivots of the secondary lever, and pivotal means connecting the main 120 lever to the secondary lever at the sides thereof between the adjacent forward and rearward pivots of the secondary lever.

6. In a scale, the structure set forth in claim 5, in combination with spring means 130

connected to one of the rearward pivots of the main lever to counterbalance a load placed on the platform, and spring means connected with the other of said forward 5 pivots to counterbalance the main lever and the scale parts carried thereby.

7. In a scale, in combination, a main lever having a pair of rearward pivots, a lever counterbalancing spring connected to one of 10 said pivots, a load counterbalancing spring, connections extending therefrom to the other of said pivots, and temperature compensating mechanism operatively connected with the aforesaid connections to vary the force 15 received from said main lever and exerted upon the load counterbalancing spring.

8. In a scale, in combination, a main lever having a rear pivot, a draft-rod connected to said pivot, a lever connected to the draft- 20 rod for actuation thereby, a counterbalancing spring, a connection between the spring and the second named lever, and thermostatic means carried by the second named lever to vary the spring connection there- 25 with to compensate for temperature changes.

9. In a scale, in combination, a lever, a yoke having arms on opposite sides of the lever, a pair of springs each connected by one end to an arm of the yoke and having 30 their other ends suitably supported, a shiftable connection between the yoke and the lever, thermostatic means carried by the lever to shift said connection to compensate for temperature changes, and means for 35 connecting to the lever a support for the goods to be weighed.

10. In a scale, in combination, a lever, a yoke having depending arms on opposite sides of the lever, a pair of counterbalancing springs each connected by one end to one of the yoke arms and having its other end suitably supported, a carrier arranged to slide longitudinally on the lever between the arms of the yoke and having pivots engaging 40 said arms, and thermostatic means carried by the lever and connected with said carrier to shift the latter to compensate for 45 temperature changes.

11. In a scale, in combination, a lever, a yoke having depending arms on opposite sides of the lever, pivotal connecting means between the yoke arms and the lever, a pivotally mounted equalizing bar, and a pair 50 of springs connected by one end to the ends of the equalizing bar and at their other ends connected to the respective arms of the yoke.

12. In a scale, in combination, a lever, a yoke having arms on opposite sides of the lever, pivotal connecting means between the 60 lever and the yoke arms, a pair of counterbalancing springs connected by one end to the arms of said yoke and suitably supported at their other ends, a dashpot carried by the yoke between the arms thereof, and a sta- 65 tionary plunger for the dashpot.

13. In a scale, in combination, a lever, spring means for resisting the movement of said lever, a shiftable connection between the spring means and lever, a thermostat attached at one end to said lever, a rigid connection between the opposite end of the thermostat and the shiftable connection and a spring attached at its ends to the shiftable connection and the lever, and means for connecting to the lever a support for the goods 70 to be weighed.

14. In a scale, in combination, an indicating drum, a weight supporting platform, a base lever system to support the same, a lever disposed below the indicating drum and substantially parallel with the same, connections between said base lever system and said lever, a spring counterbalance for said lever at the end of said drum, and operating connections between the lever and the indicating drum. 80

15. The invention as set forth in claim 14, in which the lever is provided with a variable connection to the spring counterbalance and in which a thermostat is provided upon 90 said lever to vary the said connection upon a variation of temperature.

16. In a drum scale, the combination of an indicating drum, a drum housing for supporting the same, a lever disposed below and longitudinal to the axis of the drum and fulcrumed in a support depending from the drum housing, a spring counterbalance for said lever, thermostatic means carried by the lever for varying the leverage exerted upon said spring by said lever under varying temperature conditions, and means depending from the lever and extending downwardly from the drum housing for connecting the lever with a support for the 105 goods to be weighed. 100

17. In a scale, in combination, a weight supporting platform, an indicating drum, a base lever system to support the platform, a lever longitudinally disposed below the 110 drum and fulcrumed at one end thereof, a spring counterbalance for said lever at the opposite end thereof, a draft rod intermediate the ends of the lever and connecting the same to the base lever system and operating connections between the lever and the said indicating drum. 115

18. In a scale, in combination, a drum housing and a pedestal housing, an indicating drum in said housing, a lever within 120 said drum housing and disposed longitudinally below the same, a spring counterbalance connected with said lever within the drum housing, an operating connection between the lever and the indicating drum, and a draft rod in said pedestal housing connected at its upper end with said lever and at its lower end connecting with a support for the goods to be weighed. 125

19. In a scale, in combination, a base lever 130

system, an indicating drum, a longitudinally disposed lever below the said drum, shiftable connections upon one end of said lever, a yoke connected thereto, a pair of 5 load counterbalancing springs connected to said yoke, a bifurcated draft rod connecting the base lever system with said lever, a rack pivoted upon said lever to operate the drum and a thermostat carried by the said 10 lever for shifting the said shiftable connections.

20. The invention as set forth in claim 19, in which a dashpot is connected to the yoke and in which the counterbalancing springs 15 are supported at their upper ends by an equalizing bar.

21. In a scale, in combination, a base lever system comprising a lever of the second order and a lever of the third order, a draft 20 rod connected to one of said levers, a lever of the third order connected to said draft rod, spring load counterbalancing means connected to said third order lever, and thermostatic means carried by said lever for varying the effective leverage between the lever and said counterbalancing means, whereby 25 variations in the spring due to temperature are compensated.

22. In a weighing scale in combination a 30 base housing, a pedestal, a drum housing, an indicating drum therein, load counterbalancing means within said drum housing and driving connections for the drum including a steelyard extending downward in 35 the pedestal into the base housing, a main lever of the second order having a pair of pivots fulcrumed within the forward part of the base housing, a nose iron extending rearwardly from said lever and connecting with 40 the aforesaid steelyard, an open framed supplementary lever within the base housing having a pair of fulcrum pivots disposed at the rear thereof and having provisions for preventing the upward tilting of the lever 45 under load, double pivotal connections from the said supplemental lever to the main lever at the sides thereof, a bearing frame, a double pivotal connection between said frame and the supplementary lever for supporting 50 said frame on the lever, and a check device for maintaining the bearing frame in horizontal position.

23. A base lever for a drum scale, comprising in combination a base housing, a 55 main lever of the second order having a rearwardly extending arm constituting a nose iron, said lever having a pair of fulcrum pivots and cooperating bearings at the front of the housing, a secondary lever fulcrumed 60 at the rear of the housing and pivotally connected to the main lever at a point intermediate the fulcrums, of the main and secondary levers, and a bearing frame pivotally supported entirely upon the secondary lever. 65

24. A base lever system for a scale, com-

prising in combination, a base housing, a main lever of the second order having a rearwardly extending arm constituting a nose iron, said lever having a pair of fulcrum pivots and cooperating bearings at the front of the base housing, a secondary lever fulcrumed at the rear of the housing and pivotally connected to the main lever at points intermediate the fulcrums of the main and secondary levers, and a bearing frame 75 pivotally supported at a pair of aligned pivotal points upon the secondary lever, said bearing frame being adapted to transmit the load of the goods through the secondary lever to the main lever and being independent of direct support upon said main lever.

25. In a scale, the combination of a main lever composed of an open frame portion having a pair of forwardly extending arms provided with pivots and a rearwardly extending arm constituting a nose iron portion, bearings for the forward pivots constituting a fulcrum for the main lever, a secondary lever composed of an open frame and having a pair of forwardly extending arms and a pair of rearwardly extending arms, each of said arms being provided with a pair of pivots, a bearing frame entirely pivotally supported upon the forward pivots of the secondary lever, said rear pair of pivots having cooperating bearings and forming a fulcrum for the secondary lever and a pair of pivotal connections intermediate the secondary lever and the main lever.

26. A base lever system for a weighing 100 scale adapted to be entirely housed within a housing, comprising in combination with the housing, of a pair of main lever bearings within and at the front of the housing, a pair of secondary lever bearings within and 105 at the rear of the housing, a main lever of the second order fulcrumed upon said forward bearings, a secondary lever fulcrumed by double pivots upon said rear bearings, a pair of pivot connections to impart force 110 from the secondary to the main lever at a point between the main and supplementary bearings, all of the aforesaid levers and pivotal connections being entirely within the housing, and a bearing frame supported 115 solely by a single pair of aligned pivots carried by the secondary lever, said bearing frame having portions thereof projecting without the housing to support a receiver for the goods to be weighed.

27. In a scale, in combination, a base lever system, a draft rod connected thereto, a lever connected to the draft rod, spring counterbalancing means connected to said lever, and a thermostat carried by said lever for varying the point of connection of the spring counterbalancing means and the lever.

28. In a scale, in combination, a base lever system comprising a lever of the second order and a lever of the third order, a draft 130

rod connected to one of said levers, a lever of the third order connected to said draft rod, spring load counterbalancing means connected to said third order lever, and 5 thermostatic means carried by said lever for varying the effective leverage between the lever and said counterbalancing means whereby variations in the spring due to temperature are corrected.

10 29. In a scale, in combination, a base lever system, a lever, a draft rod connecting the lever and the base lever system, a spring

counterbalancing means connected to said lever, a weight indicator, a connection between the lever and indicator, and a thermostat carried by the lever for varying the point of connection of the lever and spring counterbalancing means to compensate for variations in the flexibility of the spring counterbalancing means under varying temperature conditions. 15 20

In testimony whereof I hereunto affix my signature.

BERT W. KING.
